AIRPLANE

Charles Twining, Garden City, N. Y.

Application January 16, 1937, Serial No. 120,863

4 Claims. (Cl. 244—56)

This invention relates to airplanes and more particularly to improvements in airplanes having a propeller and its driving engine mounted for swinging movement between a position in which the propeller provides traction propulsion to a position in which the propeller provides lifting propulsion. In previous airplanes of this type, the propeller shaft has been fixed against lateral movement which has prevented free roll of the fuselage with respect to the propeller shaft when the latter is in position to provide lifting propulsion.

An object of this invention is a propeller mounting which permits relative lateral movement between the fuselage and the propeller shaft when the propeller is arranged in its position of lifting propulsion and which is provided with means for easily and accurately returning the propeller to its position of traction propulsion.

Other objects, novel features and advantages of this invention will become apparent from the following specification and accompanying drawing, wherein:

Fig. 1 is a side elevation of an airplane having its propeller mounted in accordance with the invention;

Fig. 2 is a fragmentary front view with the motor in traction propulsion position;

Fig. 3 is a fragmentary front view with the motor in its position of lifting propulsion;

Fig. 4 is a plan view of a three engine airplane with one of the engines mounted in accordance with the invention, and

Fig. 5 is a perspective view of a portion of the propeller mounting.

In Fig. 1, 10 indicates an airplane fuselage which may be of any suitable type and 11 designates the wing associated therewith. For simplicity's sake, the airplane has been disclosed as a monoplane but it is to be understood that the invention is not limited to any particular type of plane but can be utilized in connection with any desired type.

A pair of standards 12 rest on and are fastened to the top surface of the wing 11. The ring 13 has trunnions 14 journalled in the upper portions of the standards 12. The axis of rotation of the ring 13 is transverse to the longitudinal or main axis of the airplane. An engine 15 is provided with trunnions 16 which are journalled in the ring 13 with the axis of rotation being parallel to and in the same vertical plane with the main or longitudinal axis of the airplane. Preferably, the engine is of the radial cylinder type as the invention is best adapted to mounting engines of

this type. However, it is to be understood that the invention may be applied to other forms of airplane engines. A preferably compound propeller 17 is attached to the crank shaft of the engine in the usual manner including a reversing 5 bevel gear mechanism 30, and a flexible hose 15a is provided for supplying fuel to the engine.

The engine mounting above described permits movement of the engine and propellers from the position shown in full lines in Fig. 1 to the position shown in dotted lines in the same figure. In the full line position, the propellers are arranged for traction propulsion while in its dotted line position the propellers are arranged for lifting propulsion. In the latter position, the propellers 15 may be used to assist in taking off and in landing or in emergencies by providing an upward pulling force. By reason of the pivotal mounting of the engine in the ring 13, relative lateral movement of the propellers and fuselage is permitted 20 so that the fuselage may roll laterally as well as pitch longitudinally while being supported by the propellers.

The rear end of the engine casing is weighted so that the engine and propellers tend automatically to move into the dotted line position shown in Fig. 1. A latch 18 operated through the medium of a rod 19 extending into the fuselage coacts with one trunnion 14 to hold the engine and propeller in the full line position of Fig. 1. 30 Upon release of the latch 18 by actuation of the rod 19, the engine and propeller automatically assume the dotted line position shown in Fig. 1. A cable 20 passes over a pulley 21 on a post 22 and is attached to a stud 23 provided at the rear 35 end of the engine case. By means of this cable, the propellers and engine are pulled from the dotted line position of Fig. 1 to the full line position. Guide members 24 are carried by the post 22 and terminate at their upper ends in a socket 40 in which the stud 23 is received. This socket is so arranged that when the stud is seated therein, the propeller shaft is parallel with and lies in the same vertical plane as the main longitudinal axis of the airplane. The guide members 24 are arcuate in side elevation and diverge in plan and front elevation. The lower ends are so arranged that when the propellers and engine are in the position for lifting propulsion, the stud 23 engages one of the guide members upon lateral movement 45 of the propeller shaft through an arc of approximately 45° in either direction from vertical position. These guides therefore serve to limit relative lateral movement of the propellers and fuselage as well as to guide the stud into its notch. 50 55

Should the propeller shaft be at an angle to the fuselage when the cable 20 is being pulled, the guide members will bring the propeller shaft into longitudinal alinement as it is moved into its 5 horizontal position.

The plane preferably should be so constructed that the center of its total weight and load as well as the center of lift of the wings will lie approximately in the line of the normal axis of 10 the plane. Furthermore, the engine mounting preferably should be so arranged that when the propellers are in their position of lifting propulsion, the axis of the propeller shaft is in alinement with the center of gravity and center of 15 lift.

To bring the engine and propellers from the dotted line position to the full line position of Fig. 1, the engine is swung about the trunnions 14 through the medium of the cable 20 and 20 when it reaches the full line position, the latch 18 is actuated to hold the engine and propellers in such position. When it is desired to return the propellers and engine to the dotted line position, the latch 18 is released, whereupon the 25 engine and propellers swing about the trunnions 14 under the force of gravity due to the weight provided for that purpose in the rear end of the engine case.

In Fig. 4, the center engine is provided with 30 the mounting just described, while the engines at either side are mounted in the standard manner for traction propulsion only. The center engine and its propellers may be used for lifting the plane off the earth and for holding the plane 35 at any desired elevation. It is of course understood that other combinations of engines than those shown herein might also be used.

The compound propeller 17 consists of two sets of blades mounted on concentric shafts, one 40 of which is fixed to the engine shaft. Gearing 30 is interposed between the two shafts so as to effect offset and equal rotation of the two 45 shafts and sets of blades, thereby preventing the development of any turning moment in the engine case, each set of blades being of proper size and shape as to engage the equal air resistance. If desired, identical sets of blades can

be used but in such event the gearing 30 will be of such a nature as to rotate the two shafts at such speeds that the two sets of propellers will engage equal air resistance.

I claim:

1. In an airplane, a frame, a propeller and engine assembly, means supporting said assembly from said frame for limited universal movement, a stud on said engine, a socket to receive said stud when said assembly axis is parallel to the 10 longitudinal axis of the airplane, and arcuate converging guide members leading to said socket, said guide members being engageable by said stud to limit lateral movement of said assembly and to direct said stud into said socket. 15

2. In an airplane, a frame, a ring having trunnions journaled in said frame, a propeller and engine assembly pivotally supported by said ring, a stud on said engine, a socket to receive said stud when said assembly axis is parallel to the 20 longitudinal axis of the airplane, and arcuate converging guide members leading to said socket, said guide members being engageable by said stud to limit lateral movement of said assembly and to direct said stud into said socket. 25

3. In an airplane, a frame, a propeller and engine assembly, means supporting said assembly from said frame for limited universal movement, said assembly having a pointed tail, a socket to receive said tail when said assembly axis is 30 parallel to the longitudinal axis of the airplane, and arcuate converging guide members leading to said socket, said guide members being engageable by said tail to limit lateral movement of said assembly and to direct said tail into said socket. 35

4. In an airplane, a frame, a ring having trunnions journaled in said frame, a propeller and engine assembly pivotally supported by said ring, said assembly having a pointed tail, a socket to receive said tail when said assembly axis is parallel to the longitudinal axis of the airplane and 40 arcuate converging guide members leading to said socket, said guide members being engageable by said tail to limit lateral movement of said assembly and to direct said tail into said socket. 45

CHARLES TWINING.
